DIAL SELECTIVE CALLING SYSTEM

Charles W. Burcky, Park Ridge, Ill., assignor to
Teletype Corporation, Chicago, Ill., a corpora-
tion of Delaware

Application November 4, 1944, Serial No. 561,876

1 Claim. (Cl. 177—353)

1

This invention relates to telegraph switching systems and more particularly to station calling systems.

The principal object of this invention is to provide an efficient and economical station selection system.

Another object of the invention is to provide a dial calling selective system which will operate on a minimum of power with the greatest simplicity of design.

Briefly, this invention relates to a station calling system employing at a transmitting station a manually operated dial mechanism which functions as a transmitter for sending signals, and a set of manually operable keys for permutably arranging signals generated by the dial mechanism for transmission over a line to a plurality of receiving stations associated with the line. Each of the receiving stations has an automatically operable mechanism acting as a receiving distributor for receiving signals, a set of manually operable selector elements associated with the automatic mechanism and being controllable by received signals for enabling the transmitting station to select a particular receiving station for operation upon an agreement between the permutative arrangement of the keys of the transmitting station and the permutative arrangement of the selector elements at the particular receiving station being called.

Specifically, the arrangement consists essentially of a selecting system wherein the transmitter distributor at the calling station is in the form of an ordinary telephone dial. At the calling station, there is provided a set of keys which are electrically connected to five segments transversible by a brush associated with the telephone dial. By means of these keys, various permutations may be set up in accordance with the five unit code in order to select a particular receiving station. At the receiving station, the receiving distributor, which is in the form of a telephone dial, is released for operation upon the receipt of the start impulse and has associated therewith five segments similar to the five segments of the transmitting distributor. The five segments are connected to five slow-to-release relays each of which conditions a plug and jack arrangement to control marking and spacing signals. Connectible to the jacks are a set of plugs which may be connected either to the marking or spacing side of the jack in order to set up particular permutations at the receiving station. When the transmitting keys of the transmitting station are set in a permutation

2

similar to the permutations set up upon the plug and jack arrangement of the receiving station, a circuit will be completed to an output relay. At the receiving station there is provided a solenoid which is operable to perform the function of winding up the receiving distributor automatically after a signal has been received. The dial at the calling transmitter, however, is manually operated like the ordinary telephone dial, except that the same extent of movement is imparted upon each operation thereof, because upon each operation a five unit permutation code signal is transmitted, instead of a varying number of impulses.

Having reference to the drawing, the station A or central station is shown on the left-hand side of the drawing and the station B or receiving station is shown on the right-hand side of the drawing. With the arrangement according to the present invention, the operator at the control station A, through the operation of the five switches indicated generally as 11, may adjust these switches permutably in accordance with which one of a plurality of receiving stations he wishes to transmit to or to connect with. The station B is exemplary of a plurality of receiving stations which are identical in nature and wherein the plugs indicated generally as 12 may be inserted permutably into the jacks of a switchboard, indicated generally as 13, to correspond with the particular signal pertaining to the particular receiving station. In this manner, the signal which is transmitted from station A in accordance with the setting of switches 11 will be received by that station B which has its plugs 12 set in the same permutable manner into the jack of switchboard 13, as will become more clearly apparent hereinafter.

At the station A or calling station, the transmitting mechanism comprises a segmented transmitting disc 14 and a telephone dial device 15 associated with a common shaft 16. The disc 14 is fixed or stationary and the rotatable shaft 16 extends therethrough and carries a brush arm 17 affixed to the shaft. The disc 14 comprises a continuous inner ring 18 and a concentric segmented outer ring comprising a start segment 19, five impulse segments 21, 22, 23, 24, and 25, and a stop segment 26. The brush arm 17 is provided with carbon brushes 27 and 28 adapted to cooperate with and bridge electrically the inner ring 18 and the outer segmented ring. The purpose of providing solid brushes is to facilitate rotation of the brush arm 17 in both directions, as will hereinafter appear.

The telephone dial device 15 comprises a disc 29 fixed to the shaft 16 and provided with an aperture 31 for dialing the device. A fixed stop 32 is provided for limiting the rotational or clockwise movement of the dial 29. Also fixed to the shaft 16 is one end of a spiral spring 33, the other end of which is secured to a post 34 suitably mounted in the telephone dial structure. With this construction the shaft 16, when rotated clockwise through the instrumentality of dialing hole 31, will cause spring 33 to be wound up until the dialing hole or finger has been stopped by the member 32, whereupon when the finger is withdrawn and the disc 29 allowed to be released, the shaft 16 will be rotated in a 10 counterclockwise direction to its initial position under the control of the well known telephone dial governor (not shown). Also fixed to the shaft 16 is a disc 35 which is provided at suitable angular positions, radially directed from the periphery, with a pair of lugs or projections 36 and 37, which cooperate with a three-armed lever 38 pivotally mounted on a shaft 39 suitably carried in the dial structure. Lever 38 is provided with an arm 41 which cooperates with the lugs 36 and 37, an arm 42 which cooperates with a contact 43, and an arm 44 which coacts with a detent spring member 45.

In accordance with the present invention, the start segment 19 is connected by a conductor 46 to a bus bar 47. Also, segments 21 to 25 are connected by conductors 51 to 55, respectively, to the contacts 56 to 60 of five switches 61 to 65 which, in turn, are connected to the bus bar 47. A signaling line 66 is connected at station A to the bus bar 47 and at the station B to the winding of a relay 67. A plurality of similar receiving stations 70 are also connected in the signal line 66.

The armature 68 of relay 67 serves to complete a circuit, as will hereinafter appear, through contact 69 to start magnet 71 of station B. Start magnet 71 is provided with an armature 72 which is mounted on a pivot 73 and is biased in a counterclockwise direction against a stop 75 by a spring 14. The free end of the armature lever 72 is provided with a shouldered or hooked portion 76 adapted to cooperate with the end of a stop arm 77 secured to a distributor shaft 78.

Also fixed to the shaft 78 is a brush arm 79 which cooperates with a stationary face plate 81 of the receiving distributor of station B. An arm 82 is secured to the shaft 78 and cooperates with a pair of contacts 83 and 84 in a manner and for the purpose hereinafter described. Fixed to shaft 78 is one end of a spiral spring 85, the other end of which is fixed to a spring post 86. Spring 85 is normally in a wound condition tending to bias the shaft 78 in a counterclockwise direction, thereby holding the arm 77 against the shouldered portion 76 of armature 72, so that when the magnet 71 is energized, as will appear presently, the armature 72 will be attracted to withdraw the shoulder 76 from the arm 77, thus releasing the shaft 78 for rotation by the spring 85, such rotation continuing until the arm 77 strikes a limiting stop 87. When this latter rotation occurs, a cord 88 will be wound around the shaft 78. Cord 88 is fixed at one end 89 to the shaft 78 and at the other end to a screw 91 secured to the plunger 92 of a solenoid 93. When the shaft 78 has been released for rotation to bring the stop arm 77 against the stop 87, the arm 82 will have been rotated to the position shown in dotted line, whereby contact 84 will be

closed, thus completing an energizing circuit for a relay 94, from grounded battery, through contact 84, over conductor 95, through the winding of relay 94, to ground. Relay 94 when energized 10 will become locked up over a circuit extending from grounded battery 96, through a contact 97, over conductor 98, through a contact 99, then through the winding of relay 94 to ground. The energization of relay 94 also completes an energizing circuit for the solenoid 93 from grounded battery 101, through contact 102, over conductor 103, and through the winding of the solenoid 93 to ground. Moreover, immediately after releasing shaft 78 for rotation, contact 83 will close 15 to control electrical circuits, as will hereinafter appear.

When the shaft 78 has been released for rotation, the cord 88 will be wound around the shaft 78 thereby becoming taut between the shaft 78 20 and the screw 91. Then, when the contact 84 has become closed and the relay 94 energized, as just described, whereby the solenoid 93 has become energized, the plunger 92 will be drawn into the coil so that the cord 88 will become unwound from the shaft 78, at the same time rotating the shaft 78 in a clockwise direction bringing the arm 77 from the stop 87 to be re-engaged by the shoulder 76 of armature 72. During this rightward movement of the plunger 92 into the solenoid 93 a flange 104 on the solenoid plunger 92 25 will operate to open the contact 97 to break the locking circuit for the relay 94, which in turn breaks the energizing circuit for the solenoid 93. Upon de-energization of the solenoid 93 due to 30 the opening of contact 102 a spring 105 will act to withdraw the plunger 92 from the solenoid coil 93, thus slackening the cord 88 as shown in the drawing.

Like the transmitting disk 14 at the transmitting station, the disk or face plate 81 at the receiving station B is similar thereto in the segmental arrangement. This face plate 81 comprises a solid inner ring 106 to which is connected one end of a conductor 107, the other end of which terminates at the afore-mentioned contact 69. An outer concentric ring, comprising a plurality of segments is associated with the inner ring 106 and comprises, like the arrangement at the central station A, a start segment 108, five segments 109, 111, 112, 113, and 114 which constitute the code impulse segments, and a stop segment 115. The brush arm 79 is provided with a pair of carbon brushes, one cooperating with the inner ring 106 and the other with the outer segmented ring. The start segment 108 is connected by a conductor 116 to the winding of the start magnet 71. The segments 109, 111, 112, 113, and 114 are connected by conductors 117, 118, 119, 121, and 122, respectively, to the winding of relays 123, 124, 125, 126, and 127, respectively. The windings of slow-to-release relays 123 to 127, inclusive, are connected also to a common conductor 128 which terminates at the afore-mentioned contact 83. Relays 123 to 127 are each provided with a locking circuit which extends from grounded battery 129, over common conductor 131, through individual contacts 132, through the windings of the various associated relays 123 to 127, then over the common conductor 128 and through contact 83 to ground.

Each relay 123 to 127 is also provided with an armature 133 which cooperates with a marking contact 134 and a spacing contact 135, individual thereto. When a relay is energized, a marking contact is closed; and when a relay is de-

energized, a spacing contact is closed. Each marking contact 134 is connected to a marking jack 136, and each spacing contact 135 is connected to a spacing jack 137. Each armature 133 is electrically connected to the panel board 13. Five plugs 138, 140, 150, 160 and 170 are provided, one for each pair of jacks 136 and 137. Each plug is provided with a tip portion which is connectible with the jack 136 or 137, and a ring portion which connects with the panel board 13. The set of five plugs may be connected to either the marking jack 136 or the spacing jacks 137 to set up a particular permutation at the receiving station in accordance with its call signal. A series circuit through the set of plugs and through an output relay 139 may be ultimately completed therefor only when the five relays 123 to 127 have been selected by a permutation code signal which matches the positions selected by the five line plugs. Initially, however, due to the fact that the attract time of the armature 151 of relay 139 is sufficiently long to permit the brush 79 to traverse several segments before the contact 153 is closed, the lamp 155 (or other apparatus to be controlled) will not be operated until the entire code signal has been received. In this way, a circuit through the output relay 139 upon the reception of any one of a plurality of different permutation signals, and the signal required to select any given station, may be changed at any time by inserting the line plugs in the jack in any one of said plurality of different possible combinations. It is understood, therefore, that the setting of the plugs at the stations B or similar stations will be characteristic of the calling signal for that particular station.

General operation

The system according to the present invention is illustrated in the drawing in the normal stop position. In this position the brush arm 17 at the central transmitting station rests upon the stop segment 26, and the brush arm 79 at the receiving station rests upon the start segment 108. The reason for this manner of connection is so that upon the initiation of the call at the station A the mechanism at the station B will be in readiness to receive the start or initial impulse so as to initiate, in response to the start signal received from the calling station, the apparatus or mechanism at the called station. By means of the aperture 31 in the disk 29 the dial mechanism is rotated in a clockwise direction the full distance up to the stop 32. When this has been done the spiral spring 33 is wound and the disk 35 has been rotated to the position indicated by the dotted line positions 236 and 237 of lugs 36 and 37, respectively. At the initial portion of its rotation lug 37 of disk 35 acts upon arm 41 of lever 38 to rotate it to the dotted line position 241, thus opening contact 43 and causing detent 45 to hold arm 44 in a detented position. By this revolution, the brush arm 17 is rotated in a clockwise direction to bring the carbon brushes 27 and 28 into contact with the start segment 19 and the concentric solid ring 18 preparatory to transmitting the initial or start impulse, upon the closing, subsequently, of the contact 43, as will appear presently. As the disk 35 was rotated, the lug 36 was carried past the dotted position 241 of arm 41 so that when the disk 29 was released upon withdrawal of the rotating instrumentality from the aperture 31, the lug 36 acts to bring the lever 38 out of detented position to permit the closing of contact 43. As soon

as contact 43 has been closed, a circuit is completed from battery 141 through contact 43, over conductor 141, through ring 18, through carbon brush 27, over the brush arm 17, through the carbon brush 28, through start segment 19, over conductor 46, through bus bar 47, over the signal line 66, through the winding of relay 67, to ground. The relay 67, upon being energized, pulls up its armature 68 to complete a circuit from grounded battery, through the armature 68, through contact 69, over conductor 107, through ring 103, through the brush arm 79, through start segment 108, over conductor 116, and through the winding of magnet 71 to ground. Upon the completion of this circuit, the rotation of the dial or receiving distributor at the receiving station is initiated due to the fact that the armature 72 is attracted. Upon attraction of the armature 72, the arm 77 is released for rotation, energy for rotating the shaft 78 being stored in the spring 85. The brush arms 17 and 79 are thus arranged to rotate in phase with each other under the control of the well known telephone dial governor (not shown) associated with each shaft. It is to be noted that the synchronism and phase conditions are required for only one revolution of the shafts 17 and 79.

The switch device 11 comprising the switch arms 61, 62, 63, 64, and 65 is capable of being adjusted into any one of a plurality of permutable positions by employing various combinations of the switch arms in their two positions. These switches, of course, may be of any commercial form such that they may be manipulated to give a permutative setting characteristic of the station it is desired to call. Assuming that the switch arms 61 to 65, inclusive, are arranged in a permutative setting whereby the contacts 56, 58, and 60 are closed by the switch arms 61, 63, and 65, respectively, and it is desired to call a station having plugs 12 arranged in this identical setting, the operator upon operating the dial at the calling station A will be connected to one and only one station B; namely, that which is connected in a predetermined manner with the same permutative setting, that is, marking impulses on the first, third, and fifth signal intervals of the code combination. At the receiving station B, plugs 138, 150, and 170 will have been inserted in the marking jacks, and plugs 140 and 160 will have been inserted in the spacing jacks. As the brush arms 17 and 79 now rotate in synchronism they will traverse the corresponding code segments in proper timed sequence. For example, when the segment 21 is being traversed by the brush arm 17, a signal impulse is transmitted from battery 141, through the contact 43, over conductor 141, through ring 18, over brush arm 17, through segment 21, over conductor 51, through contact 56, over switch arm 61, through bus bar 47, over the signaling line 66, through the winding of relay 67, to ground. Whenever such a marking impulse is transmitted over the signaling line 66, the relay 67 becomes energized to attract its armature 68. As previously described, brush arm 17 passes over segment 108 as arm 79 passes over segment 108 to impress a start (marking) impulse upon start magnet 71. Thereafter, brush arms 17 and 79 traverse substantially simultaneously with their respective segments 21 and 109, then segments 22 and 111, etc.

As the brush arm 79 passes over the start segment 108 the arm 82 permits the contact 83 to close, thus preparing the operating circuit and

locking circuit for the slow-to-release relays 123 to 127, inclusive. In the present instance, as the brush arm 79 passes over segment 109, the brush arm 17 is passing over the segment 21. Since the switch 61 is closed, a circuit is completed to relay 67 from battery 147, through the contact 43, over conductor 141, through ring 18, over brush 17, through segment 21, over the conductor 51, through contact 56 and switch 61 to bus bar 47, whereupon the signal impulse is transmitted over the signaling line 66 to the relay 67 which becomes energized and attracts its armature 68. A circuit is thereupon completed from grounded battery, over armature 68, through contact 69 (now closed), over conductor 107, through ring 106, over brush arm 79, through segment 109, over conductor 117, through the winding of relay 123, over conductor 128, through contact 83, to ground. Relay 123 becomes energized and attracts its armatures 133 and 142. The closing of armature 142 closes its contact 132 to complete a locking circuit for relay 123 from grounded battery 129, over conductor 131, through the armature 142, through contact 132 associated with relay 123, through the winding of relay 123, over conductor 128, through the contact 83 (now closed), to ground. The armature 133 of relay 123 is attracted (as indicated by dotted lines) and closes the marking contact 134 associated therewith, and since the plug 170 associated with the jack of the relay 123 is inserted in the marking jack position, a circuit will be prepared from ground, through the ring portion of plug 170, then through the panel board 13, over conductor 144, through the armature 133 of relay 123, through the marking contact 134 thereof, over the conductor 145 to the marking jack 136 thereof, then over the tip side of plug 170 to the conductor 146.

As the brush arms 17 and 79 traverse further and contact the segment 22 at the central transmitting station and segment 111 at the receiving station, respectively, a circuit is prepared from battery 147, through contact 43, over conductor 141, through ring 18, over brush arm 17, through segment 22, and over conductor 52. But, since switch 62 is not closed, no circuit will be completed thereover, and hence, relay 67 connected to the line 66 will not be energized. Accordingly, the armature 68 will not be attracted, so contact 69 will not be closed. Therefore, no circuit is completed for relay 124, and armature 133 of relay 124 will be held at the spacing side 135 (as shown). The circuit previously described from ground 149, will be continued over the ring side of plug 138 associated with relay 124, then through the panel board 13 and the armature 133 of relay 124, then through contact 135 and spacing jack 137 thereof. The circuit will then be completed over the tip side of plug 138 to conductor 146.

As the brush arms 79 and 17 traverse the succeeding segments, circuits for relays 125, 126 and 127 will be completed depending upon whether or not contact switches 63, 64, 65 are closed. In the present instance, it is noted that contacts 63 and 65 are closed and therefore, marking impulses will be transmitted over the signaling line when segments 23, 112, 25 and 114 are traversed, and relays 125 and 127 will become energized. The plugs 150 and 138 associated with relays 125 and 127, respectively, are connected to their respective marking jacks, and circuits will be completed therethrough. Since the switch 64 is not closed, the relay 126 at the receiving

station will not be energized, and the armature thereof will rest on the spacing contact 135 thereof. The plug 140, therefore, will be inserted in the spacing jack.

With this arrangement it is seen that a series circuit is completed through the series of plugs, from ground, through the various circuits, as previously described, then through the winding of relay 139 to grounded battery. Since the output relay 139 is now energized it will attract its armature 151 and complete a circuit from grounded battery 152, through armature 151, through contact 153 (now closed), over conductor 154 to (in the present embodiment) a signal lamp 155. Of course, it is understood that the output relay 139 controls any sort of circuit such as a repeater or other electrical arrangement. For example, should it be desired to sustain the closing of the contact or contacts associated with relay 139 for a predetermined time, not less than a certain value, the relays 123-127 are made slow-to-release so that the rewind time of shaft 78 (that is, from the time contacts 84 are closed and relay 94 and solenoid 93 are operated until contact 83 is again opened) plus the slow-to-release time of relays 123-127, plus the slow-to-release time of relay 139 will give this value. For this reason, the relays 123-127 are slow-to-release.

As the shaft 78 continues its rotation, the arm 77 will strike against stop 81, and the brush arm 79 will rest upon the stop segment 115. On assuming this position the contact 84 will be closed, as previously described, to introduce battery upon the circuit for the relay 94, which, as previously described, is effective to control the energization of the solenoid 93. Cord 88 which has just been wound up on the shaft 78, will be unwound by the pulling in of the solenoid 92, thus imparting clockwise rotation to shaft 78 until the stop arm 77 is locked behind the shoulder 76 of the armature 72 of the magnet 71 which is now de-energized. The dial at the transmitting station has been returned by spring 33 to its initial position so that now both the station A and station B are in their normal rest position preparatory to sending out another call signal which may be the same as previously described, or of any other of a plurality of permutations which may be set up on the switches 61 to 65, inclusive, it being understood that the signal transmitted from the station A will be received by and cause to operate the apparatus at that station B which has its plugs 138 set in the panel board 13 in a permutative combination identical to the setting of the switches 61 to 65.

Although the present invention has been described in connection with its specific embodiment thereof, it is understood that such application is merely illustrative and not restrictive, the scope of the present invention being defined only by the scope of the appending claim.

What is claimed is:

In a selective station calling system, a transmitting station, a plurality of receiving stations, a signal line connecting said stations, transmitting means at said transmitting station comprising permutably settable switching elements and an impulsing device manipulable from a normal position to an ultimate position, said device effective upon return to normal position to impress through said switches start-stop permutation code signals upon said signal line, receiving means comprising a line relay responsive to signals impressed on said signal line, an automatically oper-

able impulsing device normally tending to operate, storing relay means electrically associated with said impulsing device, electromagnetically controlled means effective normally to restrain said impulsing device against operation, said electromagnetically controlled means responsive to the start impulse of said permutation code signals to initiate operation of said automatically operable impulsing device to distribute the signal impulses of said permutation code signals to said storing relay means, a plurality of serially associated plugs, a corresponding series of jacks, one jack associated with each storing relay, a con-

trollable instrumentality electrically associated with said plugs, whereby an energizing circuit for said instrumentality is established when said plugs are arranged in said jacks in correspondence with the permutation code setting of said settable switching elements, and further electromagnetic means effective upon completion of operation of said automatically operable impulsing device to automatically return said automatically operable impulsing device to normal position for reoperation under control of said start-stop permutation code signals.

CHARLES W. BURCKY.
